OF NEW YORK.

KNITTED NECKTIE.

1,072,471.

Specification of Letters Patent. Patented Sept. 9, 1913.

Application filed September 20, 1912. Serial No. 721,358.

To all whom it may concern:

Be it known that we, JOSEF KELLNER, a subject of the Emperor of Germany, and SIDNEY WORMS, a citizen of the United States, residing, respectively, at Brooklyn, in the county of Kings and State of New York, and New Rochelle, in the county of Westchester and State of New York, have invented certain new and useful Improvements in Knitted Neckties, of which the following is a specification.

The present improvement relates to neckties, and particularly to knitted neckties, the object thereof being to provide a knitted necktie with stripes of a different or contrasting color or colors knitted therein on a true or substantially true bias, and also to provide a bias knitted necktie having a bias knitted stripe or stripes therein of a different or contrasting color or colors, and to provide such a necktie with a narrow neck portion merging into a flaring end or ends, the manner in which the tie is knitted being shown and described in our contemporaneously pending allowed application for the process, Serial No. 721,600, filed Sep. 21, 1912, from which it will be observed that the tie is knit upon a flat knitting machine having a pair of inclined needle beds and differential tension mechanism for giving proper tension to the work as it is knitted.

In the drawings accompanying and forming part of this specification, Figure 1 is a plan view of this improved necktie; and Fig. 2 is a rear view of the larger gradually widening flaring end thereof, the opposite widened flaring end being formed the same at its rear.

Similar characters of reference indicate corresponding parts in the figures of the drawings.

The knitted necktie 2 is given an iridescent effect lengthwise thereof by knitting the same with different colored threads, as for instance a black and red or black and yellow, or any desired different colors of threads which it may be preferred to use, the colors forming as it were alternate colored rows or ribs 2' and 2'' extending lengthwise of the tie. At intervals along

throughout the length of the tie, by means of different colored threads, stripes 3 are formed, which are diagonally located cross-wise of the tie, and these stripes are located on a true bias.

55

In knitting this improved tie, the tie is started with a certain width in the machine, it being started for instance at the end 4, and by gradually throwing out of operation certain needles or stitches on one side it is 60 knitted with one edge, as 5, straight and the other, as 6, tapered, (see Fig. 2), so as to give a gradually widened flaring effect to the end when the tie is properly made, as at 7, this taper continuing until the neckband portion 8 is reached, both edges 9 of which are knitted straight. In other words, when the tie is started for instance at the widest portion of the end 4 certain needles are gradually thrown out of operation on 65 one side, as for instance the side 6, thereby resulting in a gradually widening flaring effect, while the other side remains straight until the neckband is reached, when both sides are so knitted that the edges will be 70 parallel, and then to form the other gradually widened or flared end 10 certain needles on one side are gradually thrown into operation, whereby the widened flaring end is 75 gradually obtained, until the wide portion 80 11 of the tie is knitted. At certain intervals in the tie different colored threads are shot thereinto to form the diagonal stripes. These stripes are obtained by shooting into the tie at intervals threads of another color 85 or colors, the tie and the stripes being knitted on the bias, this being obtained by racking or jogging one, as for instance the rear, needle bed during the knitting of the tie in a peculiar manner. When ordinary 90 stripes are formed the needle bed is racked alternately in opposite directions. At the same time the work is maintained under a differential tension, so that greater tension will be given to the tie along one side thereof 95 than along the other so as to prevent the stitches or loops at one side from interfering with one another by reason of their looseness, the greatest tension being given on that side where the loops would otherwise 100

be loose and thus prevent the loops from backing up on the needles and interfering with the operation of the machine. Thus, while during the knitting the stripes are 5 apparently located in parallelism and horizontally across the work, yet when the work is removed from the machine the stripes are found to be on a true bias, and this without the necessity of stretching the tie out of 10 shape, so that there is no tendency of the tie after it is finished to curl or assume any other position than its proper normal one, and in which all of the threads are of substantially the same tightness or looseness.

15 By the process described we are able to provide not only a knitted necktie having true or substantially true bias stripes therein, but we are able to provide a bias knitted necktie, that is a necktie in which the 20 stitches or needle loops run on the bias from end to end, with a bias stripe or stripes therein of a different or contrasting color or colors or shades of color. The tie, when knitted in the manner described, is then 25 formed up so that one straight edge and an inclined edge, as 5 and 6, will be brought together, whereupon the same are sewed along their edges, and where the straight edge and the flaring edge separate, as at 12, they are 30 barred, as at 13, in the manner shown in Fig. 2. Prior to the sewing, however, each end of the tie is cut and overedged to give a shaped end which in the present instance is shown as of a triangular shape 14. This 35 overedging may likewise be done with different colored threads corresponding with the body of the tie. When the tie is made up in the manner shown one edge, as 15, will be substantially straight while the opposite edge, as 16, will be of tapered form, and this straight edge may be on the outside or the inside. In the present instance the straight edge is shown on the inside, the edges 5 and 6, however, being so lapped 40 that the tie has a pair of gradually widening flaring ends of considerably greater width than the neck portion.

It will be observed that the present improved tie has its ends terminating in a 50 triangular portion which is of a single thickness or fold.

The present improved tie may have either a plain or iridescent effect with the stripes therein of a different color or colors, such 55 stripes being located on a substantially true bias during the knitting of the tie without the necessity of stretching or cutting the tie after it is made to give this result, and in the present tie all of the threads are of the 60 same tightness or looseness throughout the tie.

From the foregoing it will be observed that this improved tie is knitted flat with its lateral edges subsequently suitably con-

nected, as by sewing, as distinguished from 65 a tubular knit tie, and, furthermore, the stripe or stripes which may be of a different or contrasting color or colors, or varying shades or colors, have substantially the same appearance on both sides thereof, that 70 is to say, the stripe or stripes are of the same continuous or solid color on both sides, and the stitches or loops are not loose and flowing on the rear side of the fabric, so that in some cases the tie could, if the wearer 75 were so disposed, be turned and worn wrong side out.

We claim as our invention:

1. As an article of manufacture, a flat 80 knitted necktie having its lateral edges suitably connected, said necktie having a colored stripe or stripes of a different or contrasting color or colors knitted therein on a substantially true bias.

2. As an article of manufacture, a flat 85 knitted necktie having its lateral edges suitably connected, said necktie having a colored stripe or stripes of a different or contrasting color or colors knitted therein on a substantially true bias, said tie having a narrow 90 neck portion and one or more flaring end portions.

3. As an article of manufacture, a flat 95 knitted necktie having its lateral edges suitably connected, said necktie having a colored stripe or stripes of a different or contrasting color or colors knitted therein on a substantially true bias, said stripe having substantially the same appearance on the opposite face of the material.

4. As an article of manufacture, a flat 100 knitted necktie having its lateral edges suitably connected, said necktie having a colored stripe or stripes of a different or contrasting color or colors knitted therein on a substantially true bias, all of the stitches of said tie having substantially the same looseness or tightness.

5. A bias knitted necktie, said necktie having a colored stripe or stripes knitted 110 therein on a bias.

6. A bias knitted necktie comprising a narrow neck portion and a flaring end or ends, said necktie having a colored stripe or stripes knitted therein on a substantially 115 true bias.

7. A bias knitted necktie, said necktie having a colored stripe or stripes knitted therein on a bias, all of the stitches having the same looseness or tightness and said 120 stripe or stripes having the same solid color on both sides, and said tie having a narrow neck portion and an open flaring end or ends.

8. As an article of manufacture, a necktie 125 knitted flat with thread courses on the bias from end to end of the tie, and having a narrow neck portion merging into a gradu-

ally flaring end portion or portions, each terminating in a shaped, open end or ends, said tie having its rear lateral edges suitably connected and also having knitted 5 therein a true bias stripe or stripes of a contrasting color or colors, each of said stripes having substantially the same appearance on both sides of the fabric.

Signed at New York, this 19th day of September, 1912.
